LOOSE-LEAF HANDLING MEANS

Alfred M. Martin, Park Ridge, Ill.

Application May 1, 1937, Serial No. 140,178

5 Claims. (Cl. 129—1)

This invention relates to loose-leaf handling means more particularly for loose leaves of the type referred to in my Patent No. 1,269,479 dated June 11, 1918, and in which a number of such leaves or sheets are arranged in overlapping relation with their top or bottom margins exposed for visibility and are held in this relation by prongs which pass through some of the uniformly spaced perforations along a side margin of the leaves.

10 Such leaves are generally arranged in binders of the type referred to in my patent and specially constructed for such purpose. It frequently happens, however, that it is desirable to transfer from the binder a large number of such leaves, without disturbing their relationship, and either for temporary purposes, or for storage. The present invention, among other objects, aims to provide improved means for such purposes.

The invention is inclusive of an improved transfer fork of the general type referred to in the Wirt Patent No. 1,546,183, dated July 14, 1925, but in this instance the fork has greater adaptability to various binders now in use having different prong spacing arrangements. Also the present improved transfer fork embodies other novel and useful characteristics later herein described in detail.

The invention is also inclusive of a housing for the transfer fork which prevents spilling of the sheets therefrom, and which may also provide, with the fork, a permanent storage device, if desired.

Other objects and advantages will be apparent from the following description, taken together with the accompanying drawing, in which—

35 Figure 1 is a plan view, parts being shown in section, of the combined housing and transfer fork with leaves held thereby;

40 Figure 2 is a separate bottom view of the transfer fork;

45 Figure 3 is a partial longitudinal section taken on the line 3—3 of Fig. 1; and

Figure 4 is a cross-section taken on the line 4—4 of Fig. 1.

50 Referring to the illustrative construction shown in the drawing, the transfer fork 9 comprises an elongated bar 10 which is desirably of metal, channeled to provide somewhat upstanding edges 11 along each side thereof. Along the channeled side of the bar, that is, between the upstanding edges 11, are secured as by welding, a longitudinally aligned series of prongs 12, which, as here shown, are arcuate so as to correspond somewhat with the prongs of a loose-leaf binder. The bar 55 also has therein longitudinally aligned series of apertures 13, these being longitudinally aligned with the bases of the prongs, but being also somewhat elongated transversely of the bar. As described in the Wirt patent above referred to, the 60 binder is opened and the prongs of the transfer

fork are inserted in the perforations in the leaves desired to be transferred, intercalated with the prongs of the binder. Also as described in that patent, the apertures in the bar receive the prongs of the binder and thus avoid interference therewith.

In accordance with the present invention, however, the prongs and apertures are not disposed at regular intervals or uniformly spaced throughout the length of the bar, as in the said Wirt patent. Considering the distance between the centers of the prongs and apertures as a unit of measurement along the bar, it will be noted that in some cases, that is, between some of the pairs of prongs, there are two of these units, between other pairs, three units, and between still other pairs, four units. Also between some of the pairs of prongs there are three apertures, between others only two, and between still others only one. However, it will be noted that there is a periodicity 20 in the order of spacing the prongs and apertures, for example, the first three prongs (from left to right) have each two apertures between the adjacent prongs, of the third, fourth and fifth prongs, the third and fourth prongs have one aperture between the prongs, and the fourth and fifth prongs, three apertures, and this variation is repeated throughout the length of the bar. Some periodically irregular spacing of the binder prongs is now common practice in binders of the type referred to. The particular spacing here disclosed has been found to accommodate itself to a maximum number of various types of prong spacings common in such binders.

30 With the Wirt fork it was necessary to hold by hand the transferred leaves on the fork, but in the present invention, means are provided for this purpose. That is, in accordance with the present invention, the fork 9 with a stack of leaves 14 thereon, is intended to be received in the housing 15, in this case telescopically, the housing being of a length to receive the transfer fork wholly therein, and retain it therein by manually controllable means such as a releasable detent between the fork and housing.

35 For this purpose, the housing, which is formed in this instance of two strips of sheet metal 16 and 17 welded together along their overlapping portions to form a floor member 18, is bent to longitudinal channel shape and preferably somewhat box-shape in cross-section, its upper wall being discontinued medially to form a longitudinally extending slot 19 and leaving overhanging wall portions 20 at each side. In the present embodiment, the housing is open at its right-hand end but is partially closed at its left-hand end by a plate 21 riveted to the housing as at 22 adjacent the overhanging wall portions 20 and leaving a space 23 between it and the floor 18 of the housing.

It will be understood that the transfer fork 9 with the sheets 14 thereon may be slid into the housing from its right-hand end, the distance between the floor 18 of the housing and the overhanging wall portion 20 being approximately the width of the bar 10. The side of the housing represented by the angle member 16 provides a track for the bar, the width of the housing being just sufficient to snugly receive the bar 10 and prongs with the free ends of the prongs just contacting the opposite side of the housing represented by the angle member 17 and under the overhanging wall portion 20 at this side of the housing. Thus this side of the housing provides a guard for the free ends of the prongs which prevents spilling of the leaves 14 therefrom. This guarding effect is enhanced by the overhanging wall portions 20, since the movement of the leaves 14 is limited to the intermediate portions of the prongs exposed, when the fork is in the housing, by the slot 19 therein. I will now describe the releasable detent here shown for retaining the fork in the housing. Secured centrally of the floor member 18 of the housing, as by spot-welding 24, is a bracket 25, to which is again welded an elongated strip of resilient metal 26, extending toward the end of the housing partially closed by the plate 21. The bracket 25 is desirably set well back from the end of the housing so as to enhance the leaf-spring function of the strip 26. In order to provide resiliency of the strip, in the direction of the sides of the housing, the spring where secured to the bracket is parallel with the sides, but as it approaches the end of the housing, I have shown the strip 26 twisted as at 27 to be flat, so that there may be secured thereto, as by spot-welding at 28, a transverse member 29 which acts as a detent nose to engage the lug 30 secured at one end of the bar 10. An inclined cam surface 31 on the detent nose permits the end of the bar upon the insertion thereof to cam the spring detent aside, whereupon the further movement of the bar in one direction is prevented by the partial closure plate 21, which thus acts as a stop, and in the other direction by the detent nose 29, which after the lug 30 has passed it, springs back into position to abut this lug longitudinally. To release the detent, the flattened portion 27 of the strip 26 is extended outwardly beneath and beyond the plate 21 and is turned up as at 32 to form a thumb-piece by which the detent may be conveniently manually retracted from the lug 30, to permit withdrawal of the bar from the housing.

In order that the fork may be received with but one predetermined relationship to the housing, to properly locate the lug 30 with respect to the detent, the open or right-hand end of the housing has an obstruction 33 at one side thereof which prevents the bar 10 from being slid within this side of the housing, but does not interfere with the prongs 12.

The upturned side edges 11 of the bar 10 not only strengthen the bar but also prevent scraping of other articles by the edges of the bar, the prongs being secured to this channeled side of the bar and further preventing any scraping of the edge of the bar with any other object. The ends of the bar are also slightly turned up as at 34 for the same purpose.

The invention is not limited to details of construction here shown for purposes of exemplification. Such changes may be made as fall within the scope of the following claims without departing from the invention.

Having described my invention, I claim:

1. In loose-leaf handling means, the combination with a single fork embodying a bar and a series of free-ended prongs spaced therealong, of a channel-shape housing telescopically receiving the fork, said housing providing a guard for the free ends of the prongs, and releasable spring detent mechanism securing said telescopic relation. 10

2. In loose-leaf handling means, the combination with a single fork embodying a bar and a series of free-ended prongs spaced therealong, of a channel-shape housing telescopically receiving the fork, said housing providing a guard for the free ends of the prongs, and releasable 20 detent mechanism securing said telescopic relation, the housing having a permanently fixed partial closure whereby the fork is received therein in but one predetermined relation. 15

3. In loose-leaf handling means, the combination with an elongated bar having a series of prongs fixed longitudinally thereof, of an elongated housing telescopically receiving the bar and prongs, said housing being open at one end and the other end being at least partially closed 25 to act as a stop for the bar, a lug on the bar, a spring detent carried by the interior of the housing normally in the path of said lug between which detent and said stop the lug is received to limit movement of the bar with respect 30 to the housing, the detent having a cam surface acted upon by the bar to move the detent to permit the lug to pass in one direction. 35

4. In loose-leaf handling means, the combination of a prong carrying bar, a series of prongs spaced therealong, a channel-shape housing receiving the bar and prongs and movable relatively thereto, and spring detent mechanism releasably securing the assembled relation of the parts, said mechanism including a lug on one of the relatively movable parts and a leaf spring carried on the other relatively movable part, said leaf spring carrying a lug engaging detent nose having a cam surface thereon, said detent being adapted to be resiliently cammed away from said lug upon relative movement of the bar and housing in one direction, and a thumb-piece for manually moving the detent from said lug to permit relative movement of the parts in the opposite direction. 40 45

5. In loose-leaf handling means, the combination with a single fork embodying a bar and a series of free-ended prongs spaced therealong, of a channel-shape housing telescopically receiving the fork, said housing providing a guard for 50 the free ends of the prongs but exposing the intermediate portions of the prongs, spring detent mechanism securing said telescopic relation, and a thumb-piece connected with said detent mechanism for manual actuation thereof, said detent mechanism and said thumb-piece being wholly within said housing, and thereby protected against accidental contact. 55 60
